UNITED STATES PATENT OFFICE.

GEORGE A. KEENAN, OF LOS ANGELES, CALIFORNIA.

SHOE CLEANER AND DIRT DISPENSER.

Application filed August 17, 1926. Serial No. 129,722.

My invention is a shoe cleaner and dirt dispenser adapted to be attached to automobile running boards and the apron connected therewith to allow removal of the dirt from 5 the shoes before entering the car.

An object of my invention is to construct the running board and apron of an automobile with a shoe cleaner and a dirt dispensing device, so that the mud or dirt may be readily 10 removed from the soles of the shoes and dropped through an opening in the running board and also the apron being provided with an opening and having brushes inserted therein, so that the sole and top and side portions of 15 the shoe may be cleaned, the dirt dropping behind the apron to the ground.

Another object of my invention is to provide deflectors connected with the front scraper or scraping grid to deflect a flow of 20 air and prevent mud and dust from being thrown or blown up through the grid on or above the running board.

Another object of my invention is to provide a screen behind the apron back of the 25 brushes to prevent oil and the like from being thrown from the running gear of a car outwardly and also to block the view from the outside through the brush device.

A further object of my invention is to 30 mount an electric light or lights on the shoe brush or scraper device in order to readily illuminate it for use at night, which lights may also be left continuously burning at night when the vehicle is being used permitting the 35 lights to be used as side lights.

My invention will be more readily understood from the following description and drawings, in which—

Figure 1 is a perspective view of a combined shoe cleaner and dirt dispenser attached 40 to an automobile running board and the apron connected therewith.

Fig. 2 is a longitudinal section taken on the line 2—2 of Fig. 1 in the direction of the arrow showing the instep scraper and brushes 45 in elevation.

Fig. 3 is a vertical transverse section taken on the line 3—3 of Fig. 2 in the direction of the arrows,

Fig. 4 is a longitudinal section taken on the line 4—4 of Fig. 3 in the direction of the arrows, giving a rear view of the brushes and instep scraper, and

Fig. 5 is a perspective view of a modification in which the scraper and brushes are utilized without the scraping grid. 55

In the drawings the automobile running board is indicated by the numeral 1 and the apron connected therewith is indicated by the numeral 2. The running board has a rectangular opening 3 cut therein and the apron is also provided with a rectangular opening 4. The grid for scraping the mud off from the soles of the shoes is constructed substantially as follows and is designated generally by the 60 numeral 5. A suitable rectangular frame 6 having an upper flange 7 extending outwardly over the running board and an inwardly extending lower flange 8 is mounted in the opening 3 and preferably secured to the running board by bolts 9 or the like. A suitable mesh fabric 10 which may be of heavy woven wire or other suitable material is secured in the frame and forms a device for scraping the mud or other dirt off from the soles of the 65 shoes. This mud drops through the grid to the ground. A wind deflector 11 extends downwardly from the forward edge of the frame and is curved practically underneath the grid, as shown in Fig. 2, thus preventing 70 the mud being thrown up through the grid onto the running board and to deflect the dust from the wheels so that the same will not be blown upwardly through the grid. 75

The brush construction is substantially as 80 follows: A brush carrier 12 is secured to the apron by bolts 13 or the like fitting in the opening 4. This holder has preferably a rectangular opening 14 and has brushes which 85

are designated generally by the numeral 15 mounted therein. These brushes are preferably formed of bristle holders 16 in the form 90

of strips of suitable material such as wood having bristles 17 secured therein, the bristle 95

holders being attached to the supporting structure by bolts 18 or the like. It will be noted that the central space 19 is left open for insertion of the foot and that there are lower 100

and upper brush elements 21 and 20 arranged horizontally and the vertical brush element 105 23, these being adapted to brush the sole and the upper part of the shoe and the sides thereof.

A scraper plate S is connected to the supporting structure 12 immediately below the opening 19 by bolts or the like and is adapted 110

to scrape the mud from the arch of the shoe or any mud which clings too tight to be removed by the grid 5.

The supporting structure 12 is provided 5 with illuminated openings 24 along the top, these being elongated and having other openings 25 in the shape of stars or the like being more or less ornamental. These openings may 10 be covered with glass or suitable transparent material. The trough 26 extends partly around the supporting structure 12 and preferably has a neon light tube 27, this tube being suitably connected by electric wires to a switch in order to give illumination when the 15 shoe cleaning device is being used, or as continuous side lights when the vehicle is being operated, or when passengers are alighting or stepping into the vehicle.

The metal structure forming the trough 26 20 is preferably continued forming the screen 28 back of the brushes, this screen preventing oil or the like from being thrown from the operating parts of the automobile against or through the brushes, also restricting dust or 25 the like which would pass through the brush opening and also obscuring the view of the underneath mechanism of the car.

In the construction of Fig. 5 I illustrate 30 a shoe brush device and scraper, this being indicated by the numeral 29. The device is constructed of an angular plate 30 having a vertical flange 31 and a horizontal flange 32, the flange 32 being secured to the running board by screws 33 and the flange 31 being 35 positioned in front of the opening in the apron of a motor vehicle. In this device the brushes and the scraper are arranged substantially as shown in the other figures and this may be provided with the lamp device 40 and with the screen 28 similar to the above described construction.

A perforated mat 34 made of rubber, leather or the like may be positioned on or attached to the mesh fabric 10 and may be 45 reversible so that the mat may be on the upper side as shown in Fig. 3 or it may be reversed with the metal fabric on the top.

I also utilize a shoe sole scraper 35 which 50 is attached to one end of the frame 6 preferably by screws 36 or the like, so that the grid with the mat and the metal fabric thereon may be used if desired without the brush device with the scraper plate S, or it may be used conjointly therewith for scraping the shees to better advantage.

In order to properly illuminate the scraper 60 and brush device, a reflector 37 is secured on the upper portion of the brush carrier 12 above the openings 24, thus reflecting the light downwardly. A bracket 38 is attached to the end of the brush carrier 12 and has a mirror 39 mounted therein, this mirror being positioned to receive the light through one of the openings 25 and to reflect the same 65 lengthwise of the shoe brushing device.

It is to be understood that I may utilize the grid 5 by itself for scraping the soles of the shoes or I may use the same in combination with the brush device and the shoe sole scraper S, or may use this latter construction separately as shown in Fig. 5.

It is manifest moreover that the general construction and detail of my invention may be considerably changed to adapt the same to different automobile constructions, such changes being within the spirit of my invention as set forth in the description, drawings and claims.

I claim:

1. A shoe cleaner and dirt dispensing device comprising, in combination, a vehicle running board having an opening therein, a substantially vertical apron having an opening, a frame fitted in the opening in the running board having a scraping grid, and a brush holder frame fitted into the apron at the opening, said frame having brush holders extending longitudinally of the frame.

2. A shoe cleaner and dirt dispensing device comprising, in combination, a vehicle running board having an opening, a vehicle apron having an opening, a frame inserted in the opening in the running board, a reversible grid mounted therein, a wind deflector secured to the frame extending below the grid, a brush carrier secured to the apron at the opening, said carrier having an open space extending therethrough, bristle holders attached to the carrier on the upper, lower and side edges of the open space, bristles extending vertically and horizontally from said bristle holders, and a screen attached to the back of the carrier extending downwardly behind the bristles.

3. In a shoe cleaning and dirt dispensing device, the combination of a vehicle running board having an opening, a frame secured to the running board at the opening, a reversible grid having metallic structure on one side and a resilient structure on the other side.

4. In a shoe cleaner and dirt dispensing device as claimed in claim 3 having a shoe sole scraper attached to the frame at one end above the running board, and a wind deflector extending downwardly from the frame 115 below the grid.

5. A shoe cleaner and dirt dispensing device comprising in combination a vehicle running board having a rectangular opening therein, a vehicle apron having a rectangular opening, a frame fitted in the opening of the running board having a grid mounted therein, a shoe brush carrier attached to the apron at the opening, said carrier having a rectangular opening, bristle holders extending longitudinally of the carrier at the upper and lower portion of the opening and having bristles extending towards each other, and having vertical bristle holders attached to the ends of the brush carrier at the opening 120 125 130

and bristles therein extending horizontally.

6. In a shoe cleaner device, the combination of a vehicle apron having an opening, a shoe brush carrier secured to the apron at the opening, said carrier having brush elements extending along the top, bottom and sides of the opening, the brush elements being spaced apart at the center part of the carrier, and a scraper being attached to the carrier at 10 such space.

7. In a shoe cleaner device, the combination of a vehicle apron having a substantially rectangular opening therein, a frame fitting in said opening and having a flange bearing

against the outside of the apron, the said frame having an opening therethrough to insert the foot, and a scraper blade at the lower portion of the said latter opening.

8. In a shoe cleaner device, as claimed in claim 7 the frame having a brush holder 20 mounted on each side of the scraper blade, and brush bristles secured therein, the said bristles extending inwardly from the said frame.

In testimony whereof I have signed my 25 name to this specification.

GEO. A. KEENAN.
